UNITED STATES PATENT OFFICE.

CHARLES F. CROMMETT AND ORRIN J. CROMMETT, OF CHELSEA, MASSACHUSETTS.

TURBINE.

1,110,423.

Specification of Letters Patent. Patented Sept. 15, 1914.

Application filed November 10, 1913. Serial No. 800,050.

To all whom it may concern:

Be it known that we, CHARLES F. CROMMETT and ORRIN J. CROMMETT, citizens of the United States, and residents of Chelsea, in the county of Suffolk and State of Massachusetts, have invented certain new and useful Improvements in Turbines, of which the following is a specification.

This invention relates particularly to single stage impulse turbines impelled by the expansion of an aeriform fluid such as air, carbon dioxid, sulfur dioxid or ammonia, under pressure, and it has for its object to provide a turbine of this class in which the working agent or gas under pressure expands at and within the periphery of a rotor and is exhausted from opposite sides of the rotor, the gas impelling the latter and thus doing work at the expense of heat taken from the gas while passing through the rotor.

The invention is embodied in a turbine adapted for use as a part of an apparatus for producing liquid oxygen. The working agent may be highly compressed and very cold air discharged against the blades of the rotor and allowed to expand while passing from the periphery toward the axis of the rotor, the expansion resulting in a further reduction of temperature and in the liquefaction of a considerable part of the oxygen, provision being made for the separation of the liquefied oxygen from the unliquefied oxygen and other gases, in the casing of the turbine.

The invention consists in the improvements which we will now proceed to describe and claim.

Of the accompanying drawings:—Figure 1 represents a longitudinal vertical section of a turbine embodying my invention. Fig. 2 represents a side elevation of the same. Fig. 3 represents a section on line 3—3 of Fig. 1, the rotor being shown in side elevation. Fig. 4 represents a section on line 4—4 of Fig. 1.

The same reference characters indicate the same parts in all the figures.

In the drawings:—*a* represents a casing, the central portion of which forms a rotor chamber 12 having a circular inner wall concentric with the periphery of the rotor hereinafter described. Through said wall extends a nozzle 13 arranged at a tangent to the circular inner wall, and adapted to conduct a working agent such as air under

high pressure and a very low temperature, tangentially into the rotor chamber. The bore of the nozzle may be either cylindrical or tapered to decrease its diameter at its inner end. We have shown two nozzles 13 located at diametrically opposite sides of the rotor chamber, and it is obvious that any desired number of nozzles may be employed. The casing is preferably provided with two fixed internal flanges or abutments 14 at opposite sides of the rotor and forming the sides of the rotor chamber. A shaft *c* is journaled in bearings *b* in the heads of the casing, said bearings preferably including thrust members 17 between which are interposed antifriction balls 18. A rotor *d* is affixed to the shaft and has a circular periphery concentric with the wall of the rotor chamber.

The preferred construction of the rotor is as follows: 180 represents a hub keyed to the shaft and provided with outwardly projecting spaced-apart flanges 19 having circular outer margins which form the periphery of the rotor, said flanges forming the sides of an annular space 20 constituting the outer portion of an exhaust conduit extending through the rotor, said space being open at the periphery of the rotor and having its bottom formed by the hub 180 as shown by Fig. 4. The space or conduit portion 20 is in a plane perpendicular to the shaft. Buckets 21 are secured in slots formed for their reception in the flanges 19 and extend across the space 20. The buckets are tangentially arranged relatively to an imaginary circle concentric with the shaft and between the latter and the periphery of the rotor, the preferred inclination of the buckets being as shown by Figs. 3 and 4. The buckets are preferably thin metal blades curved as shown to present concave deflecting faces to a jet of the working agent delivered by the nozzle 13. From the bottom of the annular space or conduit portion 20, lateral conduit portions or passages 22 extend in opposite directions through the sides of the rotor, said passages, four of which are shown, (although the number may be greater or less), being formed in the hub 180.

The hub is elongated as shown by Fig. 1, so that its length is considerably greater than the width of the annular conduit portion 20. This elongation of the hub pro-

vides sufficient material to compensate for the interruptions of the continuity of the hub by the passages 22, so that these passages, extended as shown inwardly 5 through the hub into the closest possible proximity to the shaft, do not materially weaken the hub. The inner sides of the rotor flanges 19 are oppositely inclined so that the annular conduit portion 20 increases in width from the periphery of the rotor inwardly as shown by Fig. 1, and the lateral conduit portions preferably increase in diameter from their inner ends outwardly, provision being thus made for 10 the expansion of the working agent after it passes the buckets.

It will now be seen that the working agent after impinging on the buckets and imparting rotation to the rotor, is directed inwardly by the buckets and guided by the annular conduit portion 20 inwardly in a plane perpendicular to the rotor axis, and then outwardly by the lateral passages or conduit portions 22, in opposite directions and in 20 paths substantially parallel with and close to the axis.

The working agent exhausts partly in liquid form as liquid oxygen, and partly in gaseous form, into exhaust chambers 25 formed by the extended end portions of the casing at opposite sides of the rotor. These chambers are provided with gas outlets 26 in their upper portions, and liquid outlets 28 in their lower portions through which the 30 gas and liquid oxygen pass from the casing.

The exhaust chambers 25 are of uniform shape and capacity. The gas outlets 26 and liquid outlets 28 are preferably arranged respectively at the upper and lower portions 40 of the casing as shown in Fig. 1, so as to obtain as great a difference in direction of the liquefied and unliquefied particles of gas as possible, in order to effect a complete separation of the liquid and gas. The mixture of 45 liquefied and unliquefied gas leaves the rotor as near the shaft as possible and in paths substantially parallel with the shaft. The tendency of the liquefied particles to resist any change in direction of flow is greater 50 than the tendency of the unliquefied particles, owing to the fact that the momentum of a given volume of liquefied gas is seven hundred and fifty times the momentum of an equal volume of unliquefied gas, its mass being seven hundred and fifty times greater. Now, as the particles lose their velocity and 55 therefore, their momentum, while moving parallel with the shaft, the unliquefied particles having less momentum readily yield 60 to a change of direction of flow and rise to the top of the exhaust chambers and pass out at the outlets 26. The particles of liquefied gas, having a much greater momentum than the unliquefied particles, continue in the 65 original path parallel to the shaft, thus

separating themselves for the direction of flow of the unliquefied particles and strike the outer sides of the exhaust chambers and fall by gravity to the liquid outlets 28.

The advantages of the described provisions for conducting the working agent from the buckets through the rotor first inwardly in a plane perpendicular to the axis, and then laterally in paths substantially parallel with the axis, and discharging the exhaust 70 into chambers at opposite sides of the rotor and in as close proximity to said axis, are the reduction to the minimum of the velocity of whirl of the working agent and of its friction on the guiding surfaces, the equalization of the exhaust pressure on the rotor, and the elimination of end thrust. The advantages of the curvature of the buckets are maximum efficiency in utilizing the impact 75 of the working agent, and in deflecting the working agent inwardly. The inner walls of the lateral passages 22 are preferably inclined from the points 27, and curved between said points and the sides or ends of the hub, to deflect the exhaust working agent 80 outwardly with the minimum of friction.

We claim:—

1. A turbine comprising a casing having a circular rotor chamber and a nozzle tangential to the inner wall of the rotor chamber, and adapted to direct a working agent thereinto, a shaft journaled in said casing, and a rotor on said shaft having tangential buckets at its periphery formed and arranged to receive the impact of the working agent and to deflect the same inwardly 95 toward the rotor axis and an exhaust conduit formed to guide the deflected working agent first inwardly in a plane perpendicular to the axis, and then outwardly from opposite sides of the rotor in paths substantially parallel with and in close proximity to the axis, said conduit being formed to permit the expansion of the working agent during its inward passage through the rotor, the casing 100 also having exhaust chambers of uniform size at opposite sides of the rotor.

2. A turbine comprising a casing having a circular rotor chamber and a nozzle tangential to the inner wall of the rotor chamber, and adapted to direct a working agent thereinto, a shaft journaled in, said casing, and a rotor on said shaft having tangential buckets at its periphery formed and arranged to receive the impact of the working agent and to deflect the same inwardly toward the rotor axis and an exhaust conduit formed to guide the deflected working agent first inwardly in a plane perpendicular to the axis, and then outwardly from opposite 115 sides of the rotor in paths substantially parallel with and in close proximity to the axis, said conduit being formed to permit the expansion of the working agent during its inward passage through the rotor, the cas- 120

ing also having exhaust chambers of uniform size at opposite sides of the rotor, gas outlets at the upper portions of said chambers, and liquid outlets at the lower portions 5 of the chambers.

3. In a turbine of the character described, a rotor comprising an elongated shaft-receiving hub, flanges projecting outwardly from the hub and forming the sides of an 10 annular exhaust conduit portion which is open at the periphery of the rotor and has its bottom formed by the hub, said annular portion being in a plane perpendicular to the rotor axis and increasing in width from 15 its outer margin inwardly, lateral exhaust conduit portions extending in opposite directions from the bottom of said annular portion through the sides of the hub in close proximity to the axis and substantially parallel therewith, and tangential buckets in 20 said annular conduit portion formed and arranged to deflect a working agent into said conduit.

4. In a turbine of the character described, 25 a rotor comprising an elongated shaft-receiving hub, flanges projecting outwardly from the hub and forming the sides of an annular exhaust conduit portion which is open at the periphery of the rotor and has 30 its bottom formed by the hub, said annular portion being in a plane perpendicular to the rotor axis and increasing in width from 35 its outer margin inwardly, lateral exhaust conduit portions extending in opposite directions from the bottom of said annular portion through the sides of the hub in close proximity to the axis and substantially parallel therewith, and tangential buckets in 40 said annular conduit portion formed and arranged to deflect a working agent into said conduit, the buckets being curved and having concave deflecting faces.

5. A turbine comprising a casing having a rotor chamber, a nozzle tangential to the

wall of the rotor chamber, and adapted to direct a working agent thereinto, and exhaust chambers at opposite sides of the rotor chamber, a shaft journaled in the casing, and a rotor on said shaft having tangential buckets at its periphery formed and 50 arranged to receive the impact of the working agent and to deflect the same inwardly toward the rotor axis, and an exhaust conduit adapted to guide the deflected working agent first inwardly in a plane perpendicular to the rotor axis and then laterally from 55 opposite sides of the rotor and simultaneously into said exhaust chambers, said conduit increasing in width from its outer margin inwardly to permit the expansion of 60 the working agent.

6. A turbine comprising a casing having a rotor chamber, a nozzle tangential to the wall of the rotor chamber, and adapted to direct a working agent thereinto, and exhaust chambers at opposite sides of the rotor chamber, a shaft journaled in the casing, and a rotor on said shaft having tangential buckets at its periphery formed and 65 arranged to receive the impact of the working agent and to deflect the same inwardly toward the rotor axis, and an exhaust conduit adapted to guide the deflected working agent first inwardly in a plane perpendicular to 70 the rotor axis and then laterally from opposite sides of the rotor and simultaneously 75 into said exhaust chambers, said conduit increasing in width from its outer margin inwardly to permit the expansion of the working agent said buckets being curved to form 80 concave deflecting faces.

In testimony whereof we have affixed our signatures, in the presence of two witnesses.
